Primary Examiner — Wan Laymon(74) *Attorney, Agent, or Firm* — Stoel Rives LLP(57) **CLAIM**

The ornamental design for a hip brace ice pack, as shown and described.

DESCRIPTION

FIG. 1 is a front isometric view of a hip brace ice pack.

FIG. 2 is a rear isometric view thereof.

FIG. 3 is a front view thereof.

FIG. 4 is a rear view thereof.

FIG. 5 is a left view thereof, the right side being a mirror image.

FIG. 6 is a top view thereof, the bottom view being a mirror image.

FIG. 7 is a front view of a hip brace and the hip brace ice pack in a disassembled configuration.

FIG. 8 is a front view of a hip brace and the hip brace ice pack in an assembled configuration; and,

FIG. 9 is a perspective view of the hip brace and the hip brace ice pack of FIG. 7 strapped onto a human body.

The broken lines form no part of the claimed design. The broken lines showing portions of a human are for the purpose of illustrating environment and form no part of the claim. The dash dot dash lines in FIG. 7 is a reference line for the purpose of illustrating the position of attachment.
